UNITED STATES PATENT OFFICE.

WILLIAM A. MARQUA, OF CINCINNATI, OHIO.

BABY-CARRIAGE.

SPECIFICATION forming part of Letters Patent No. 498,440, dated May 30, 1893.

Application filed February 2, 1893. Serial No. 460,753. (No model.)

To all whom it may concern:

Be it known that I, WILLIAM A. MARQUA, a citizen of the United States, residing at Cincinnati, in the county of Hamilton and State 5 of Ohio, have invented a certain new and useful Improvement in Baby-Carriages, of which the following is a specification.

My invention relates more especially to improvements in drop or reclining backs for 10 baby-carriages, the novel features of which being fully hereinafter explained and particularly pointed out in the claims.

In the accompanying drawings, Figure 1 is a longitudinal elevation of the main portion 15 or body of a baby-carriage embodying my invention, with the back in its closed position for supporting the child when sitting up, the running-gear and wheels of the vehicle being omitted; Fig. 2 a view similar to Fig. 1, but 20 with the back inclined or thrown outward at an angle on its hinges for supporting the child in a semi-reclining position; Fig. 3 a broken longitudinal section of my invention, with the back in the position shown in Fig. 2; Fig. 4 a 25 transverse section on line α , α , Fig. 2, looking rearwardly as indicated by the arrow; and Fig. 5 a detail perspective view of one of the slotted side rods or stays.

A represents the bottom of the carriage- 30 body; a and a' the side-rails supported by vertical bars or posts b , b' , those b' being the tail-end ones which are preferably somewhat greater in height than the others; and B the back or tail-board, mounted on hinges B' , at 35 the rear end of said bottom.

C, C' , are slotted stay-rods or braces pivotally connected at their rear ends to the back B by means of ears D, the latter being fastened on the side-bars d of said back prefer- 40 ably near the outer or upper ends thereof.

c , c' , are horizontal bolts, whose shanks project outwardly from the side-rails a , a' , near said rear-posts b' , passing through the slots in said stay-rods, and having washers c' and lock-nuts or thumb-screws c' on their outer threaded ends, whereby the hinged back B is firmly held, either at the desired inclination away 45 from the said rear-posts, or closed upright between said rear-posts.

E, represents a flexible-filling or side-curtain stretched between the rear-posts b' and the side-bars of the back B, preferably formed in

a folding or expandible manner similar to the leather in a bellows or accordion, or the flexible material in a folding-fan, as clearly shown 55 in Figs. 2 and 3. One edge of each flexible-filling E is fastened to a side-bar of the back, and the other edge to the adjacent rear-post, and sufficient space is allowed between said side-bars of the back and the rear-posts to ac- 60 commodate said flexible filling or curtains in their folded or collapsed position, as seen in Figs. 1 and 4.

In the operation of my invention, the back B may be inclined on its hinges outwardly 65 from the body, and readily adjusted to any angle within the scope or limit of the slots in the side stay-rods or braces C, C' , and firmly held in such outward position, or in its closed position between the rear-posts, by means of 70 the thumb-screws, and in case said thumb-screws and bolts become loose accidentally or otherwise, the flexible-fillings would catch and hold the said back, having the child's head resting against it, safe from falling and thus 75 preventing injury to the child or damage to said back. The side-fillings E, when the back is dropped into reclining position, also protect and shield the child's head from draft and ex- 80 cessive light, especially when it is reposing or asleep.

It is obvious that my reclining back can be used with or without the filling E, but I prefer the latter for the reason that there would be an unsightly opening at both sides when 85 said back is thrown outward, exposing the child's head to draft, light, and other obvious disadvantages.

Instead of arranging the stay-rods to operate on the outside of the body rails, it is ob- 90 vious that they could be made to project and operate back of said rails within the uphol- stery or side cushions, but any necessary re- pairs thereto would be difficult, as well, also, the original construction thereof.

I have shown in dotted lines, the usual seat F, which is adjustable longitudinally on its supports, to move rearwardly for proper contact with the back B when the latter is ar- ranged or set in a reclining position.

It is obvious that the stay-rods could be made longer and curved into an arc or sector if desired, and the slots and side-filings made of such length as to permit the back to be

dropped to a horizontal position, but the construction shown, I have found in practice to be the desired one for the purposes herein stated. It is also obvious that, if desired, said 5 adjusting stay-rods could be dispensed with, and the hinged-back B simply provided with the flexible and collapsing side curtains or fillings E, to support it when thrown outward into said reclining-position and shield the re- 10 posing child from draft and light, as aforesaid. In that event any suitable catch or latch device could be used to connect or hold the back upright when closed.

I claim—

15 1. In a baby-carriage the combination with the body having upright side-pieces, of a back B hinged at its lower edge or bottom, slotted side-stays or braces C, C', and thumb-screw fastening-devices c, c², the latter engaging the 20 slotted portions of said braces and the said upright-sides of the body, and the rear ends of said braces hinged or pivotally connected to ears D on said back, substantially as herein set forth.

2. In a baby-carriage, the combination with 25 a body A having vertical sides, of a hinged tail-board or back B, slotted stay-rods or braces C, C', thumb-screw fastening-devices c, c², and flexible and collapsing fillings or side-curtains E, said stay-rods being hinged or pivotally 30 connected at their rear ends to said back, and the curtains or fillings E stretched between and connected at their opposite ends to the rear ends or posts of said sides of the body, and to said back B, respectively, substantially 35 in the manner and for the purpose specified.

3. In a baby-carriage, the combination with the body having vertical-sides, of a tail-board or back B hinged to said body, and a pair of flexible and collapsing side fillings or curtains 40 E interposed or stretched between said hinged-back and vertical-sides, and connected at both ends thereto substantially as and for the purpose specified.

WILLIAM A. MARQUA.
